FRED EDWARD FANGER, OF MEXICO, MEXICO.

ATTACHMENT FOR TYPEWRITERS.

1,338,565.

Specification of Letters Patent. Patented Apr. 27, 1920.

Application filed July 30, 1919. Serial No. 314,261.

To all whom it may concern:

Be it known that I, FRED EDWARD FANGER, a citizen of the United States, and a resident of Mexico, D. F., Republic of Mexico, have invented a new and Improved Attachment for Typewriters, of which the following is a description.

My invention relates to an attachment for typewriters whereby the user of the typewriter may know at any time and instantly how many lines may still be written on the unused portion of the paper inserted in the machine.

The general object of the invention is to provide an indicating attachment of the character referred to having various characteristics and advantages, among which are the following: The attachment may be readily applied to standard typewriter machines in use or embodied in the machine at the factory; the device is applied to the machine by securing the casing to the frame of the typewriter and the prime mover to the axle of the platen roller; the attachment presents a neat appearance; the index means is such as to indicate the number of lines typed and this regardless of whether the writing be single, double, or triple space, or any combination of these; the indicating means includes a pointer and a dial, one movable relatively to the other, either the dial being arranged to turn relatively to the pointer, or vice versa; means is provided to set the indicating means by manual turning of the dial or pointer, according to which is arranged to turn, and the setting may be done before inserting the paper or after the paper has been inserted in the machine, the operator noting at what point the indicator should be set depending upon the place the paper occupies in the typewriter at the time the setting is done, whereupon the device automatically registers or indicates the exact number of lines which may still be written on the unused portion of the paper; by indicating the number of unused lines the indicator means enables the operator to readily calculate the number of lines that have been written.

Reference is to be had to the accompanying drawings forming a part of this specification, it being understood that the drawings are merely illustrative of one example of the invention.

Figure 1 is a top view of my typewriter

attachment illustrating the same applied to a typewriter shown in part;

Fig. 2 is a longitudinal vertical section.

The letter A indicates the usual axle of the platen roller B, and C indicates the adjacent portion of the typewriter frame.

In carrying out my invention, a part 10 is provided to be attached to the axle A, said part as seen in Fig. 2, being tubular for its major portion to fit over said axle and it is secured to the latter by any suitable means as for instance, set screws 11. The member 10 is provided with an operating element to be grasped by the user and this may consist as indicated at 12 of the usual milled handwheel which ordinarily is directly applied to the axle A.

The prime mover 13 or initial drive element of the gearing for the indicator means is in fixed relation to the axle A and here is shown as integral with the tubular portion of the element 10. Said drive member 13 is here shown as a gear wheel and it is in driving engagement with a second wheel 14 loose on a stud shaft 15, said shaft being secured to a flange 16 on a casing 17. The casing flange 16 is secured to the frame C of the typewriter by any suitable means such as screws, one of which is indicated at 18, Fig. 2. Integral with or otherwise in fixed relation to the driven wheel 14 is a wheel 19 which in turn is in driving engagement with a wheel 20, the wheels 19 and 20 in the form illustrated in Fig. 2 being bevel gear wheels. The turning of the wheel 20 gives relative movement to a dial and pointer, one of which is actuated by said wheel 20. Obviously, either the pointer or dial may revolve in practice in response to the turning of the drive wheel 13 with the platen axle A. In the form shown in Fig. 2, the dial, 22, is adapted to be turned, said dial being mounted on a sleeve 21 which at one end constitutes a bushing in the hub of the driven wheel 20. The pointer 23 is secured to the end of a spindle 24 which extends through the bushing 21. In front of the dial and pointer is a glass front 25 resting on a bead 26 and secured by a clamp ring 27 threaded onto the cylindrical top portion of the casing 17. On the spindle 24 at the opposite end from the pointer 23 means is provided for manually turning the spindle and the pointer for setting the indicator. The setting means in the present instance in-

110.

cludes a pinion 28 on the spindle 24 and in engagement with a pinion 29 on the counter-shaft 30 supported in the casing 17, said shaft 30 having a milled wheel 31 or equivalent handle element. The manner of setting in practice depends on whether the indicating means provides for turning the pointer or the dial. In any event the setting of the indicator to establish the proper relative positions of the pointer and the markings on the dial can be effected before the paper is inserted in the machine by turning the axle A and the indicator drive means, or this may be done by turning the handwheel 31 which permits of setting the indicator after the paper has been inserted in the machine. In the operation of the device when the axle A and the platen roller are turned, the drive element 13 will turn at the same speed. Said drive element 13 in turn actuates the wheels 14, 19, and 20, the latter giving movement to either the dial or pointer, in this instance the dial. Thus, by properly calculated gearing for each line space which the typewriter platen turns, the drive wheel 13 turns in a similar direction at a corresponding speed, the movement being finally transmitted to the dial which in turn moves a corresponding distance.

The dial 22 preferably is marked as shown in Fig. 1 with three annular concentric zones or circles of divisions and numbers. Each subdivision on the outer or largest circle corresponds to one single-space turn of the platen; the middle zone or circle indicates by each sub-division, one double-space turn of the platen; while each division of the smallest or inner circle indicates one triple-space turn of the platen. Thus, it is seen that the outer circle is divided into sixty spaces, the middle one into thirty spaces, and the inner circle into twenty spaces or the ratio of three of the first to one of the last being the proportion of the single to the triple spacing.

I would state in conclusion that while the illustrated example constitutes a practical embodiment of my invention, I do not limit myself strictly to the mechanical details herein illustrated, since manifestly the same can be considerably varied without departure from the spirit of the invention as defined in the appended claims. For example, the number of driven elements in the drive gearing supported by the casing for actuating the indicating means and the character of the driven and drive elements may be varied, as may also the particular means for giving relative movement to the pointer or

dial in setting independently of the drive elements of the indicator means.

Having thus described my invention, I claim:

1. A typewriter attachment of the class described including indicator devices comprising a pointer and a dial, one of which is adapted to be turned relatively to the other, a spindle mounting the turnable indicating device, a driven element through which said spindle extends and is adapted to be turned by the turning of said driven element, a drive element adapted to be secured to the axle of the platen roller of a typewriter and having driving connection with said driven element, and drive means connected with said spindle, said spindle being adapted to be turned by the last-mentioned drive means and relatively to said driven element for setting the turnable indicator device independently of said driven element.

2. A typewriter attachment of the class described, including indicator means comprising a pointer and dial, actuating means for one of the same, means adapted to be secured to the axle of the platen roller to drive said actuating means, a drive train for one of the indicating elements, and a spindle adapted to be driven by said drive train and carrying that indicating element to be actuated, said drive train being manually operable to set the last mentioned indicator element independently of the actuating means and first-mentioned drive element.

3. An attachment for typewriters to indicate the number of lines remaining to be written on the paper in the machine, the same including an indicator dial and a pointer, the one adapted to turn relatively to the other, and means to drive the turnable indicating element with the turning of the platen roller, said dial presenting three concentric zones bearing sub-divisions corresponding respectively to single, double and triple line spacing.

4. An attachment for typewriters to indicate the number of lines remaining to be written on the paper in the machine, the same including an indicator dial and a pointer, the one adapted to turn relatively to the other, and means to drive the turnable indicating element with the turning of the platen roller, said dial presenting three concentric zones, the outer zone being divided into sixty sub-divisions, the intermediate zone into thirty sub-divisions, and the inner zone into twenty sub-divisions.

FRED EDWARD FANGER.
